UNITED STATES PATENT OFFICE.

CHARLES A. DIES, OF CHICAGO, ILLINOIS.

SLICING-MACHINE.

1,331,958.

Specification of Letters Patent. Patented Feb. 24, 1920.

Application filed February 12, 1919. Serial No. 276,473.

To all whom it may concern:

Be it known that I, CHARLES A. DIES, a citizen of the United States of America, and a resident of Chicago, in the county of Cook, State of Illinois, have invented certain new and useful Improvements in Slicing-Machines, of which the following is a specification.

This invention relates to the type of 10 slicing machines in which a straight cutting blade is drawn in a diagonal direction through the substance to be sliced, and has for its object:

To provide a simple and efficient structural formation and association of parts 15 of a durable and economical construction, and adapted for ready and rapid operation, all as will hereinafter more fully appear.

In the accompanying drawings:—

20 Fig. 1 is a plan view of a slicing machine embodying the present invention adapted to a power driven means for continuous operation.

Fig. 2 is a front elevation of the same.

25 Fig. 3 is a detail horizontal section on line $\alpha^3-\alpha^5$, Fig. 2.

Fig. 4 is a plan view showing the invention adapted to a lever operating means.

Fig. 5 is a front elevation of the same.

30 Fig. 6 is a detail longitudinal section on line $\alpha^8-\alpha^6$, Fig. 4.

Like reference numerals indicate like parts in the several views.

Referring to the drawings, 1 designates 35 the bed plate of the machine formed with the usual vertical guide plate 2 near one side to provide a guide and side abutment for the substance operated on.

3 designates the cutter blade or knife 40 arranged transversely of the bed plate 1 and carried and guided by means now to be described.

4 designates a pair of side members or standards secured to the bed plate 1 in separated relation to each other and in transversely spaced relation to the vertical guide plate 2 aforesaid. The standards 4 are formed with guide slots or tracks 5 in inclined relation to the horizontal plane of 50 the bed plate 1 of the machine, and in the present construction as shown in Figs. 2 and 5, each slot or track comprises two angular portions 5' and 5'' with the upper and outer angular portion 5' having a greater 55 inclination from a horizontal plane than the

companion lower and inner angular portion 5''. Such formation of the guide slots or tracks 5 in connection with the radius links 7 hereinafter described, are adapted to impart a very effective rocking movement to 60 the cutter blade 3 in its cutting movement diagonally through the material.

6 designates a cross-pin secured to one end of the cutter blade 3 and having sliding engagement in the inclined slots 5 aforesaid 65 to constitute the guiding and connecting means for such end of the cutter blade.

7 designates a pair of radius links between the upper ends of which the other end of the cutter blade 3 is pivotally attached by 70 a cross-pin 8. At their lower ends the links 7 are pivotally connected to a pivot bracket 9 fixed on one side of the bed plate of machine as shown.

10 designates an operating hand lever 75 fixedly attached to the links 7 in any usual manner and adapted to impart a swinging motion to said links in a powerful and effective manner and so that with a downward pivotal motion of said links a downward diagonal movement is imparted to the adjacent end of the cutter blade 3, and simultaneously therewith the cross pin 6 and inclined slots 5 are adapted to impose a like movement upon the other end of the cutter blade and in consequence will preserve an approximately horizontal position during its movement in an inclined path through the material or article operated on.

In the structure embodying a constantly 90 operating or power driven machine, shown in Figs. 1 and 2 of the drawings:—

11 designates a driving shaft revolvably mounted in bearing brackets 12 on the side of the vertical guide plate 2 and provided with 95 an operating hand wheel 13 or other driving connection. The shaft 11 is also provided with a crank disk 14, the crank pin 15 of which is adapted for operative engagement in an elongated slot 16 formed in one of 100 the radius links 7 as shown. The links 7 as well as the other parts of the continuously operatable machine just described, will be of a like construction to that heretofore described in connection with the lever operated machine.

17 designates a stop or gage pin having a sliding movement in a horizontal orifice in the guide plate 2 and disposed at the required distance in advance of the cutter 110

blade 3 to constitute a stop or gage for the material operated on, as the same receives a forward step-by-step movement by hand in a continued use of the machine.

5 18 designates a spring preferably of the plate type, secured at one end to the guide plate 2 and at the other end to the outer portion of the gage pin 17, with a normal tendency to retract said pin 17 from the 10 path of the substance operated on.

15 19 designates an operating lug or ear on one of the radius links 7, which when said links and associated parts of the machine are in a raised condition, is adapted to contact with the outer end of the gage pin 17 and force the same inward into the path of the article operated on, and maintain such gage pin in such position during the initial 20 part of the slicing operation.

20 20 designates an angle bracket or standard fixedly secured to the bed plate 1 in line with the standards 4 aforesaid, so as to be to one side of and not interfere with the article to be sliced.

25 21 designates an adjustable angle clamp head having a vertical sliding adjustment on the angle bracket 20 by means of a clamping screw 22 and elongated slot as shown. In such construction the lower horizontal flange 23 is adapted to engage beneath the leaf or top of the table on which the slicing machine rests, with a view to provide a convenient and substantial means for securing the machine in place in a detachable manner.

30 Having thus fully described my said invention what I claim as new and desire to secure by Letters Patent, is:—

35 1. In a slicing machine having a side guide plate and a transversely movable cutter having a guiding radius link at one end, the combination of a stop pin having transverse movement in said guide plate, and a

40 spring tending to retract said stop pin, the stop pin having operative relation with the aforesaid radius link so as to be advanced by said link in a final movement thereof, substantially as set forth.

45 2. In a slicing machine, the combination of a bed plate having a vertical side guide plate, a standard secured to said bed plate in transversely spaced relation to the side guide plate and formed with an inclined guide slot, the outer portion of said slot having a greater inclination from a horizontal plane 55 than the inner portion of the slot, a cutter blade one end of which has guiding engagement with said slot, a radius link pivotally attached to the bed plate and pivotally connected to the other end of the aforesaid cutter blade, and means for imparting movement to said radius link, substantially as set forth.

50 3. In a slicing machine, the combination of a bed plate having a vertical side guide plate, a standard secured to said bed plate in transversely spaced relation to the side guide plate and formed with an inclined guide slot, the outer portion of said slot having a greater inclination from a horizontal plane 55 than the inner portion of the slot, a cutter blade one end of which has guiding engagement with said slot, a radius link pivotally attached to the bed plate and pivotally connected to the other end of the aforesaid cutter blade, and means for imparting movement to said link, the same comprising a driving shaft, means for rotating said shaft, and a crank disk carried by said shaft, the link aforesaid having an elongated slot for 60 engagement with the crank pin of said crank disk, substantially as set forth.

65 Signed at Chicago, Illinois, this 1st day of February, 1919.

CHARLES A. DIES.
